CLAIM

The ornamental design for a photograph or document holder, as shown and described.

DESCRIPTION

FIG. 1 is a perspective view of a photograph or document holder, showing my new design;

FIG. 2 is a top plan view thereof;

FIG. 3 is a front elevational view thereof;

FIG. 4 is a rear elevational view thereof;

FIG. 5 is a left side elevational view thereof; and

FIG. 6 is a right side elevational view thereof.

The undisclosed bottom view is plane and unornamented.
